UNITED STATES PATENT OFFICE

102,806

DESIGN FOR A DISPLAY COUNTER

Erskine D. Thompson, Burlingame, Calif., assignor to Standard Oil Company of California, San Francisco, Calif., a corporation of Delaware

Application October 19, 1936, Serial No. 65,367

Term of patent 3½ years

To all whom it may concern:

Be it known that I, Erskine D. Thompson, a citizen of the United States, residing in the city of Burlingame, county of San Mateo, State of California, have invented a new, original, and ornamental Design for a Display Counter, of which the following is a specification, reference being had to the accompanying drawing, forming a part thereof.

In the drawing:

Figure 1 is a side view in perspective of a display counter and Figure 2 is a top plan showing my new design. A portion of Figure 1 is fragmentarily shown.

I claim:

The ornamental design for a display counter, as shown and described.

ERSKINE D. THOMPSON.
